ARTICULATE CAR JOINT

Filed March 30, 1926

Inventor,

S. P. Buck.

UNITED STATES PATENT OFFICE.

STERLING P. BUCK, OF BALTIMORE, MARYLAND.

ARTICULATE CAR JOINT.

Application filed March 30, 1926. Serial No. 98,474.

This invention relates to articulate joints, and especially to an improved type of articulate car-joints.

There are two main types of articulate car-joints, viz, the single-center type and the dual-center type. Those who are familiar with such devices understand that there is at least one advantage in the single-center type, but also know that there are certain 10 disadvantages in the forms of single-center joints heretofore known to the public.

One object of the present invention is to overcome several of the above mentioned disadvantages and to provide a thoroughly 15 safe and practical sub-type of articulate joints having all of the advantages and none of the disadvantages of the single-center joints heretofore known.

This type of articulate joint is characterized by two concave sphere-segments which embrace a sphere or spherical member in their cavities or concave sides and are thereby held separate from one another while their convex surfaces are embraced by means 25 which hold them in working contact with the sphere or spherical member so they are free to turn to a limited extent in all directions.

Other objects and important features are pointed out or implied in the following details of description, in connection with the 30 accompanying drawings, in which:—

Figure 1 is a view partly in side elevation and partly in central vertical section, showing one form of the invention in connection with a truck-bolster and two car-end channel-beams, the section of the latter being in a different plane than that in the middle part of the figure.

Figure 2 is a top plan view of the form 40 shown in Fig. 1, the car-end beams being omitted.

Figure 3 is a top plan detail view of one of the car-connection members, a part of this member being broken off.

Figure 4 is a fragmental detail view, the section being taken along the line 4—4 of Figure 1.

Figure 5 is a detail, in vertical section, of a modification in which the substantially 50 spherical member is formed integrally with the retaining yoke.

Figure 6 is a modified form in which the sphere-segments extend both upward and downward from the necks of the car-connections and are seated in upper and lower sockets or concavities.

Figure 6^A is a bottom plan view of the upper-socket member of Figure 6.

Figure 7 is a modified form in which the sphere-segments are one above the other. 60

Similar reference characters correspond to similar parts throughout the several views. The truck-bolster is shown at T, and the car-end beams at C. A socket-member 10 is riveted or otherwise secured on the truck-bolster and has therein a concavity 11 which not only receives and embraces two sphere-segments 12, but, being imperforate, it also receives and retains a liberal supply of lubricating material with which it lubricates the 70 segments 12 and a sphere 13 throughout a long period of operation of the car-joint. Such lubricating material is indicated where the numeral 11 refers to the concavity, but it will be seen (Fig. 4) that the space between the segments is wider at the ends and top than at the middle, and extends half-way up the sides of the ball 13, so the latter receives lubrication even when the supply becomes relatively low. 75

A retaining yoke 14 is secured on the member 10 by means of bolts 15 which also assist the rivets in securing the member 10 in place on the truck-bolster, lock-nuts being provided on these bolts as shown in broken lines in 80

Fig. 1: The yoke 14 is apertured and screw-threaded at 16 and has an adjusting screw 17 threaded therein and provided with a rectangular top part for effecting its adjustment to compensate for wear of the working parts and thereby avoid looseness of the articulate joint. For effecting and maintaining adjustments of the screw 17, I provide a plate or disk 18 having a central aperture which fits around the rectangular part of the screw 17 and has spanner-receiving apertures 19 therethrough, which apertures also receive one or more bolts 20 threaded into the yoke 14 and combining with the disc 18 for securing the screw 17 against accidental turning; but when a spanner is applied in two or more of the apertures 19 while the bolt or bolts 20 are removed, then, by turning the spanner, the proper adjustment can be made, and the bolt or bolts 100 20 can be replaced for securing the screw 17 in its adjusted position.

To prevent water and other foreign substances from passing along the car-end connections 21 and entering the concavities 22 110 (Figures 3 and 4) of the segments 12, I provide each of these segments with an upstand-

ing flange 23 which leads the foreign matter away from the space between the segments, and onto the downwardly and outwardly inclined top of the socket of the member 10, whence such foreign matter passes away from the socket. To exclude dust and other matter that may be flying in the air, a cover or plate 23 is centrally apertured to permit the screw 17 to extend therethrough, which screw holds the plate 23 in place for covering the cavity over the ball 13. By raising this plate or cover 23, a convenient entrance is made for the injection of lubricating material, and when such material is injected, it gravitates into the socket 11. Each member 21 is formed with a comparatively narrow neck 25, and enough clear space is provided above and below this neck to admit of a vertical deflection of several degrees to compensate for deflection of the car-bodies in consequence of changes of grade of the rail-ways; and enough clear space is allowed laterally of these necks to permit of a lateral deflection of about 30° , on each side, of each car-body, with respect to the central longitudinal plane of the car-bodies; so the total deflection of the two articulated-car-bodies at each side of said plane, amounts to about 60° . If desired, an even greater amount of deflection can be provided by narrowing the sphere-segments, and by narrowing the yoke as at 114 of Figure 5, or at 214 of Figure 6, or at 314 at Figure 7. The lateral deflection, of the necks of the parts 21, 221 and 321, is also dependent on the relative widths of the lateral flanges or webs of these respective necks. These parts may be varied as to their dimensions, to suit the different types of trucks and car-ends to which they are to be attached. In Figure 7, the necks 321 are relatively thin, but as the space between the segments 312 is (as shown) wider than necessary, these necks can be made thicker than here shown, if the space between the segments is made narrower.

Each of the connections 21 includes an apertured plate through which rivets extend for securing it to the channel-beam C, and also includes a horizontal plate having its free edge formed with a channel or groove 21^a to embrace the contiguous edge of the channel-beam or car-end member C, thereby adding great strength, rigidity and security to the car-end. This construction also saves the time and expense of drilling and riveting through these horizontal parts, at the same time preserving the original strength which would be lessened by drilling therethrough.

The structure shown in Figure 5 is recommended principally for its minimum first cost, for use on freight trains, mining trains, etc. For adjusting this member, the relatively thick base can be planed away at its bottom surface. Its base flanges 114^a (one of which is absent because of the removed sec-

tion) correspond to the wider but thinner base flanges 14^a of Figure 2. These thicker base flanges are apertured at 114^b to receive securing bolts such as shown at 15 (Figures 1 and 2). A lubricating duct is shown at 113^a in the spherical member 113, and has a threaded plug-socket in which a plug may be screwed for closing it.

The structure shown in Figs. 6 and 6^a includes a concave-socket member 210 having bolt-holes therethrough for reception of the securing bolts 15, and is secured on the truck-bolster T in the same manner as shown in Figures 1 and 2 (by bolts or rivets or both), the yoke 214 also being secured by these bolts. The concavity 211, at the far side of the concave socket member 210, extends up to a plane slightly above the lower one of the four parallel and contiguous dotted lines, or nearly to the horizontal center of the ball 13 (the same being true as to the absent section of Figure 6). The yoke 214 has depending flanges 214^a for confining between them an upper socket-member 217 which has its far side extending down to a plane slightly below the upper one of the four parallel and contiguous dotted lines (just above the center of the ball 13). Each of these depending sides is shown at 26 in Figure 6^a and each is formed with an arcuate groove 27 which holds a compressible packing strip 28 which may be of soft wood or other suitable material for closing the space between the lower and upper socket members 210 and 214. Only one of the packing strips 28 is shown in Figure 6^a, the other one being omitted to more clearly show the retaining groove 27 therefor. Similar retaining grooves are provided in the lower socket-member 210, as shown by the two lower parallel dotted lines at 29, and each retaining strip is fitted in a groove 27 and a groove 29. The ends of the retaining strips 28 are in contact with the convex surfaces of the sphere-segments 212, in all positions of the latter within the socket formed by the members 210 and 214, so this socket is entirely sealed against the entrance of foreign matter and against the exit of lubricating material, assuming, however, that the total deflection is not over 30° , according to the proportions here shown; and allowing for a lap of the ends of the packing strips at the limits of the deflections, but, by making the necks 225 sufficiently narrow, so each of them occupies not more than 45° of the circumference of the spherical socket, the parts 26 and 28 can be made long enough to occupy 90° , respectively, so they will at all times keep closed the spaces between the segments 212 even when the parts 221 are deflected to an angle of 45° with respect to one another. However, I am not aware of any railway curve that would cause a deflection of more than 40° , so at least 5° are

allowed as a factor of safety, and for lap of the parts 26 and 28 beyond the edges of the space which contains the lubricating material, thereby assuring retention of the store 5 of such lubricating material.

An inlet opening 30 is provided in the top of the socket-member, and a corresponding inlet opening 31 is provided in the yoke 214, so lubrication can be injected through these 10 openings for filling the space between the segments 212. This space always maintains the same capacity, even though its shape is changed by deflection of the segments in the sockets. The opening 31 may 15 be closed by a screw-plug 32 or by other appropriate means.

For the purpose of compensating for wear, I may provide two or more adjusting screws 218 which can be screwed in for 20 pressing the upper socket member down and thereby compressing the strips 28 in the grooves 27 and 29. In Figure 6^a the locations of two adjusting screws 218 are indicated by dotted circles, such locations not 25 being indicated in Figure 6, because it would cause confusion with the plug 32. Lock-nuts 220 or other appropriate means may be provided for securing the screws 218 in adjustment. This form of the invention is ad- 30 vantageous because of the excellent lubricating qualities, as explained in the foregoing, and also because of the relatively large area of wearing surface, of both convex and concave faces of the segments 212, also be- 35 cause of the convenience of adjusting and lubricating, these operations being conveniently performed through a trap-door in the floor of the truck, by using socket-wrenches for turning the screws and lock-nuts, thus 40 eliminating the danger and drudgery of getting under the car-body for such purposes. In this form, having the upper and lower bearing and wearing surfaces of the seg- 45 ments 212, these segments present large bearing surfaces, so are very durable and strong.

While 40° is the maximum deflection which has been found necessary in all working conditions, a greater amount of deflection may be desirable to avoid breakage of the joint 50 in case of derailment of one of the car units. In case one of the car units, in an accident, should turn entirely upside-down, its seg- 55 ment 212 would rotate and thereby prevent breaking its neck 225.

In the form shown in Fig. 7, the parts 310, 312, 314, 315, 317, 318, 320, 321 and 325, correspond, in function, to the respective parts 210, 212, 214, 215, 217, 218, 220, 221 and 225, of Figure 6. This figure 7 shows 60 several modifications which may be used in connection with either form of sphere-segment shown in the other figures; for instance, the lower part of the member 310 is apertured for receiving bolts to secure it to 65 upstanding flanges of a channel-beam or of

two angle-beams; and the yoke 314 has its vertical end plates formed with legs 314^a which straddle the member 310 and rest upon supporting lugs 310^a, thereby cooperat- 70 ing with the bolts 315 for very rigidly securing the members 310 and 314 to one another. The bolts 315, respectively, may be between the ball 13 and the end plates of a yoke 314, so that by tightening them, they may be caused to spring the top part of the yoke 75 downward sufficiently for taking up any looseness resulting from wear. However, it is preferable to provide an adjustable upper socket member 317, adjusting screws 318 and lock nuts 320. 80

In each form of the invention here shown, each member 21, 221, and 321 is adapted for rotary motion in every direction independently of the motion or rest of its companion, and in all forms except Fig. 5, the ball 13 85 is free for rotary movement in all directions independently of the motion or rest of either of the contiguous sphere-segments. In each form of the invention, the radius of the con- 90 cave side is greater than or at least one-half the length of the radius of the convex side, thereby providing ample wearing surfaces of the concave side and the ball which fits thereagainst, while also providing ample clearance between the upper extension of the 95 concave side and the adjusting screw of Figure 1, or the neck of the part 113—114 of Figure 5.

Although I have shown several forms of the invention, I do not intend to limit my 100 patent protection to these forms, nor to the exact details of construction and arrangement of the parts of any one of these forms.

What I claim as my invention is:

1. In an articulate car-joint, the combination of two sphere-segments each having a concave side opposite to its convex side and provided with means to secure it to a car-body, containing means securable to a truck and holding said sphere-segments against 110 other than rotary movements therein while permitting the latter to turn in all directions with respect to one another, and retaining means in contact with the concave sides of said sphere-segments for securing 115 the latter in working engagement with said containing means.

2. The structure defined by claim 1, means to adjust said retaining means and to hold it in different adjustments for eliminating 120 excessive looseness of the sphere-segments between their containing means and their retaining means.

3. In an articulate car-joint, the combination of two sphere-segments provided with means to secure them to two car-bodies respectively, concave means to contain the convex sides of said segments and support them on a truck in the relation to permit them to turn in all directions with relation to the 125

- truck and to one another while securing them against other than rotary movements, each sphere-segment having a concave side, and a retaining member having a convex part between and against the concave sides of said sphere-segments for holding them in working engagement with said concave means.
4. In an articulate car-joint, the combination of two concave sphere-segments provided with means to secure them to two car bodies, a spherical member in the concavities of both of said sphere-segments, and means securable on a truck and embracing the convex sides of the sphere-segments and combining with said spherical member for holding them in the relation for preventing them from moving non-rotatably while permitting them to have independent rotary movement in all directions with relation to one another.
5. In an articulate joint, the combination defined by claim 4, means being provided for adjustment of said spherical member with respect to said sphere-segments and for securing it in its different adjustments.
6. In an articulate car-joint, the combination of a socket member provided with means to secure it to a truck, two sphere-segments seated for rotary movements in the socket of said socket-member and secured against other than rotary movements and provided with means for securing them to two car-bodies respectively, and means for securing these sphere-segments in said socket and holding them in spaced relation to one another and thereby preventing them from interfering with one another during their respective rotary movements.
7. In an articulate car-joint, the combination of a socket-member provided with means to secure it to a truck, two sphere-segments seated for rotary movements and held against other than rotary movements in the said socket-member and each provided with means to secure it to a car-body, and means including a yoke for securing said segments in said socket-member and holding them in proper working correlation with the latter, said yoke being provided with means to secure it to said truck.
8. An articulate-car-joint-member including a sphere-segment and a car-connecting element, the car-connecting element including an apertured upright plate and a horizontal plate, the horizontal plate being formed with a groove to receive and be secured by a flange of a structural beam while fastening elements extend through said upright apertured plate and beam for securing this car-connecting element to a car-end beam, substantially as described.
9. An articulate-car-joint-member including a sphere-segment having a concave side opposite to its convex side, a car-connecting element including a neck united with the sphere-segment and extending radially outward therefrom and terminating on a part provided with means to secure it to a car-end, and two side elements which are substantially divergent from one another and from said necks.
10. An articulate-car-joint-member including a sphere-segment having convex and concave sides concentric with a common center, a car-connecting element including a neck united with said convex side and diverging outward therefrom and provided with means to secure it to a car-end, and two sides which converge towards one another from said neck.
11. An articulate-car-joint member including a sphere-segment having convex and concave sides concentric with the common center, and a car-connecting element including a neck united with said convex side and diverging outward therefrom and provided with means to secure it to a car-end, said concave side having a radius which is at least one-half the length of the radius of said convex side, substantially as shown.
12. In an articulate-car-joint, the combination of two sphere-segments each having a concave side opposite to its convex side and provided with means to secure it to a car-body, containing means securable to a truck and holding said sphere-segments therein while permitting the latter to turn in all directions with respect to one another, retaining means in contact with the concave sides of said sphere-segments for securing the latter in working engagement with said containing means, and means to adjust said retaining means and to hold it in different adjustments for eliminating excessive looseness of the sphere-segments between their containing means and their retaining means.
- In testimony whereof I affix my signature.

STERLING P. BUCK.
